UNITED STATES PATENT OFFICE

2,513,933

COLD CATHODE MAGNETRON

Anatole M. Gurewitsch, Schenectady, N. Y., assignor to General Electric Company, a corporation of New York

Application March 28, 1946, Serial No. 657,716

5 Claims. (Cl. 250—27.5)

1

This invention pertains to a novel construction and energizing circuit for cathodes of the cold emission type for electron discharge devices, particularly for those of the magnetron type.

As is well known in the art of electron discharge devices, there are certain advantages to the use of cathodes of the cold emission type which make them preferable to the hot emission type in situations where their disadvantages do not preclude their use. For example, the fact that the cold cathode requires no separate heating circuit, as does the hot emission type, considerably simplifies tube manufacture and operation. This feature, together with the fact that it generally requires no electron emissive coating, facilitates the design of rugged and durable tube constructions which can better withstand the physical shocks to which electron tubes may be subjected in practical usage. Moreover, as is particularly the case with magnetrons, the cathode may be subjected to undesirable overheating and destruction by bombardment by electrical particles within the tube. Because of their generally more durable construction cold cathodes are more able to withstand such effects thereby lengthening the life of the tube and the cathode in operation.

The invention will be better understood from the following description when considered in connection with the accompanying drawings in which Fig. 1 represents a magnetron incorporating the improved cathode of the invention; Fig. 2 represents a detailed view of the cathode, and Fig. 3 represents a cross sectional view of the anode-cathode structure taken along the line 1—1 of Fig. 1.

Referring to Fig. 1, it will be noted that the magnetron comprises the conventional elements including an anode 10 and permanent magnetic pole pieces 11 and 12 which supply the magnetic field for operation of the magnetron in the well known manner. Useful output power of the magnetron may be taken from the output loop 13 inserted within one of the anode cavities 14 in the usual manner. The entire ensemble including the novel cathode 15 to be hereinafter described, is supported in any suitable manner within an evacuated envelope 16 which may be of metal, glass, or any of the equivalent materials common in the art. A potential difference between the anode and cathode may be imposed by any source of intermittent or continuous voltage such as the pulser circuit 17 which has its negative terminal connected to the cathode 15 and its positive terminal connected to the

2

anode through the ground connections 18 and the metallic envelope 16. Cylindrical cavities 19 and 20 are provided in the magnetic pole pieces 11 and 12, respectively, to permit the introduction of suitable leads 21 and 22 to the cathode sections 23 and 24, respectively.

The cathode 15 comprises two generally cylindrical sections 23 and 24 having closed end portions 25 and 26, respectively, and juxtaposed open ends 27 and 28. The cathode sections 23 and 24 are coaxially mounted as shown and maintained in fixed spaced relation by means of the insulator 29 which maintains electrical insulation between the members 23 and 24, at least as respects the direct current and low frequency components of the various electrical currents involved in the operation of the tube.

As will be seen from the drawing, the juxtaposed edges of the open ends 27 and 28 are so constructed as to form sharp or pointed surfaces which will facilitate the induction of an electrical discharge when a voltage difference exists between the two sections 23 and 24. Alternatively, the open ends 27 and 28 may be provided with a series of sharp points or serrations, not shown. As is well known, sharp edges or pointed surfaces create a high potential gradient in the neighborhood of the edge or point which gradient facilitates the initiation of a discharge.

It is to be understood, therefore, that any construction in which a series of sharp points are juxtaposed in such manner that a potential difference will readily create a discharge, may be used in the place of the construction shown.

The cathode section 23 is connected by lead 21 directly to the negative terminal of the pulser circuit 17. The section 24, on the other hand, is connected to ground, i. e., to the anode through lead 22 and a relatively high impedance such as resistance 30. It will be understood, therefore, that when a potential difference is applied between the anode 10 and the cathode 15 by the pulser circuit 17 the same potential difference will initially be imposed across the gap formed by the edges 27 and 28. Immediately, however, as the current across the gap produces a potential drop in the resistance 30, the potential of the section 24 will drop below that of the anode and tend to approach the potential of the section 23. In the process, a sufficient number of electrons will be released by the gap to permit the operation of the anode and cathode as a conventional magnetron. If the supply should diminish, the current through resistance 30 will likewise di-

minish thereby raising the potential of member 24 to increase the energization of the gap.

The foregoing construction will be found to be particularly useful in connection with electron tubes of the magnetron type for the reason that in operation there is an inherent tendency of such type of tube to return a considerable number of electrons to the cathode with resultant overheating and destructive effect on the cathode. Furthermore, it is particularly adapted to magnetrons operated in pulsing fashion, such as pulsing oscillators in radio location work where the tube is required to oscillate only during periodic short intervals. This is for the reason that the gap will suffice to supply enough electrons for the short period required, whereas it might not in all cases be sufficient to supply the electrons for sustained operation.

While I have shown and described particular embodiments of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. An electron discharge device comprising a cathode of the cold emission type comprising juxtaposed members electrically insulated from each other and forming a gap of high electric field intensity, an electrode in electron receiving relation to said cathode, means connected to said electrode and to one of said cathode members for applying an operating voltage between said electrode and one of said cathode members, a relatively high impedance connecting said electrode to another of said cathode members whereby said operating voltage is applied to said impedance and said gap in series to induce an electrical discharge at said gap.

2. An electron discharge device comprising an anode and a cathode of the cold emission type comprising spaced cylindrical members electrically insulated from each other and having juxtaposed sharp edges forming a gap of high electric field intensity, means connected to said anode and one of said spaced cylindrical members for applying an operating voltage between said anode and one of said cathode members, a relatively high resistance connecting said anode to the other of said cathode members whereby said operating voltage is applied to said resistance and said gap in series to induce an electrical discharge at said gap.

3. An electron discharge device of the magnetron type comprising a cathode of the cold emission type comprising juxtaposed members electrically insulated from each other and forming a gap of high electric field intensity, an anode, a relatively high impedance connecting

said anode to one of said cathode members, and means connected to said anode and said other of said cathode members for imposing a positive potential upon said anode with respect to said cathode.

4. An electron discharge device of the magnetron type comprising a cathode of the cold emission type comprising juxtaposed members electrically insulated from each other and forming a gap of high electric field intensity, an anode positioned in electron receiving relation to said cathode, means connected to said anode and to one of said cathode members for applying an operating voltage between said anode and said one of said cathode members, a relatively high resistance connecting said anode to the other of said cathode members whereby said operating voltage is applied in said resistance and said gap in series to induce an electrical discharge at said gap.

5. An electron discharge device of the magnetron type comprising a cathode of the cold emission type comprising spaced coaxial cylindrical members electrically insulated from each other and having juxtaposed sharp edges forming a gap of high electric field intensity, an anode spaced from said cathode, means connected to said anode and to one of said cathode members for imposing a positive potential upon said anode with respect to said one of said cathode members, a relatively high resistance connecting said anode to the other of said cathode members whereby said positive potential is applied across said gap at the initial moment of operation to initiate an electrical discharge in said cathode.
